LLEWELLYN T. BARNES, OF SEA CLIFF, NEW YORK.

CARBURETER.

1,134,365.

Specification of Letters Patent.

Patented Apr. 6, 1915.

Application filed December 1, 1913. Serial No. 803,877.

To all whom it may concern:

Be it known that I, LLEWELLYN T. BARNES, a citizen of the United States, and resident of Sea Cliff, in the county of Nassau and State of New York, have invented certain new and useful Improvements in Carbureters, of which the following is a specification.

This invention relates to carbureters for use with internal combustion engines and my improvements have particular relation to a novel means devised by me for regulation of the fuel and air supplies whereby the proportionate quantities of fuel, as well as 10 the main and auxiliary air supplies may be furnished in proper quantities to suit varying cylinder requirements. In other words my improved carbureter is so arranged that the adjustment of a single moving part 15 thereof effects in proper ratio the fuel supply, the main air supply, and the auxiliary air supply, whereby under different degrees of adjustment the user can depend upon the admission into the cylinder of a correctly 20 proportioned mixture of fuel and air without the necessity of separately adjusting the several supplies.

In the drawing accompanying this application, Figure 1 is a vertical side sectional view of my improved carbureter, the fuel supply member being shown in full lines, and Fig. 2 is a vertical front sectional view of the same.

In the preparation of my improved carbureter I take advantage of the known characteristics of the Venturi tube as a passage for the main air supply, both on account of the increased velocity of traverse through a passage having a constricted throat, and 25 also because the constricted portion of the tube lends itself to the convenient regulation in capacity of air passage by means of certain other instrumentalities employed by me.

45 In said figures the letter *a* indicates a Venturi tube having the constricted portion *a'*, said tube *a* serving for the passage of a main air supply, and said tube having fitted in its upper end a cup-like member *b* supplied with a covering of wire mesh or other screen to filter the air entering said tube. Said Venturi tube is surrounded with a jacket, as *a''*, forming a chamber *a''*, and having threaded tube orifices *a'''* in order that 50 said chamber *a''* may be included in the ex-

haust passage from the engine. Said Venturi tube is mounted upon a base member *c*, by means of vertical posts *c'*, supported from said base and passed through lugs, as *c''*, extending from the jacket *a''*. The said lugs support the Venturi tube with its jacket 60 slidably upon the posts *c'*, and said Venturi member is thus vertically adjustable. Means are shown in this application for maintaining the Venturi member in any fixed position vertically with respect to the posts *c'*, it being my intention to provide supporting means which are capable of holding said Venturi member in a fixed position and of adjusting it vertically, the posts *c'* serving 65 as guides. Obviously said Venturi tube may be held in a certain fixed position with relation to the posts *c'* as by a set screw *c'''*.

The base member *c* is adapted for connection with the intake of an internal combustion cylinder, and is provided with a jacket *c''* providing a space, with threaded pipe openings *c'''*, that the chamber *c''* formed by said jacket may serve for the passage of water from the circulatory system of the 80 engine.

The axis of the passage in member *c* is in alignment with the axis of the Venturi member, the lower opening of said Venturi member approaching said member *c* over an intervening space. Threaded within the member *c*, to be capable of vertical adjustment is a flared inlet member *d* in opposed relation to the lower end of the Venturi tube *a*, said venturi lying axially partway within the entrance to said member *d*, and being capable of varying the space between the peripheral edge of the Venturi member and the inner surface of the member *d* to regulate the size of the clearance therebetween 90 with the vertical adjustment of the Venturi member, whereby the auxiliary air supply which enters through the member *d* may be suitably regulated.

Entered within the member *c* as through 100 stuffing box *e* in the wall thereof is a fuel pipe *e'*, which fuel pipe is bent within said member *c* and continued axially thereof into the lower portion of the Venturi member *a*. Said fuel pipe carries at its free end within the Venturi tube a tubular nozzle member *f* whose external contour tapers in opposite directions, from an intermediate point, as *f'*, at which point the girth of said member *f* is 105 at its maximum, forming an annular shoul-

der, the member *f* presenting said shoulder in about the horizontal plane of the constricted portion *a'* of the Venturi tube. At said point of its maximum girth the member 5 *f* is provided with radial orifices *f'* for the supply of liquid fuel received from the fuel pipe *e'*. Within the upper end of member *f* there is entered the pointed end of a needle 10 valve *g*, the stem of which valve is threaded through a boss *h* of a spider *h'* which is fitted within the upper end of the Venturi tube.

The inner wall of member *c* may be provided with an orifice *i* communicating from 15 the water jacket, said orifice being closed and controlled with a valve *j* that is threaded through a bushing *j'* in the water jacket *c'*, said valve also being provided with a stuffing box *j''*. The purpose of this orifice *i* with 20 controlling valve is to admit water from the water jacket into the fuel mixture when desirable for employment therewith, as when there is a full load or over load on the engine.

25 It will be obvious from the construction and arrangement of the members comprising my improved carbureter that the movement of the Venturi member upon its guides *c'* has the effect of regulating the capacity of 30 the main air supply, the fuel supply, and the auxiliary air supply. The enlarged body girth of member *f*, when exactly in the horizontal plane of the restricted portion of Venturi member *a*, has reduced the passage 35 between said members to the minimum, and also the needle valve *g* has diminished the supply of liquid fuel to orifices *f'* to the lowest point in accordance with the set adjustment of said needle valve. Also in the 40 said position of the Venturi member its lower end is in such relation to the flared member *d* that the clearance between said members is at its minimum and proportioned to admit the correct auxiliary air supply 45 from the fuel mixture. It is equally obvious, under the arrangement of parts described, that the movement of Venturi member *a*, away from member *d*, increases in cor-

rect ratio, the fuel and air supplies, to suit the varying requirements of the engine as to 50 load and speed.

My improved carbureter is adapted for use with any liquid, and as heated by the engine exhaust and by the hot water from the circulatory system, is particularly adapted 55 for use with kerosene.

While shown and described as arranged vertically it is evident that the Venturi tube may be disposed in a horizontal or other position.

30 I claim:

1. In a carbureter, the combination of an auxiliary air supply tube with a flaring inlet, a Venturi supply tube arranged in axial relation thereto, a fuel supply pipe extending 65 axially through said auxiliary tube and entered within said Venturi tube, and a fuel supply member extending from said pipe, said member having an annular shoulder with radial orifices directed toward the constricted portion of said Venturi tube, together with a needle valve adjusted within 70 said fuel supply member, said Venturi tube being axially adjustable to at one movement regulate the fuel supply and both air supply 75 75

2. A carbureter having a Venturi tube for air supply and a fuel supply member disposed axially therein, said fuel supply member having radial orifices directed toward 80 the constricted portion of said tube, one of said members being movable axially with respect to the other, a valve for said fuel supply member, an auxiliary air supply member in axial relation to said Venturi tube, means for regulating the air, fuel and auxiliary air supplies proportionately with the movement of said movable member, and a heating jacket for said Venturi tube. 85

Signed at borough of Manhattan in the 90 county of Nassau and State of New York this 28th day of November A. D. 1913.

LLEWELLYN T. BARNES.
